DeWalt®, 2002 Catalog, No. DW920K-2, Heavy-Duty $\frac{1}{4}$ " (8mm) 7.2V Cordless Two-Position Screwdriver, pp. 29 & 31 Cordless.*Primary Examiner*—Cathron C. Brooks*Assistant Examiner*—Austin Murphy(74) *Attorney, Agent, or Firm*—Michael P. Leary; Charles E. Yocum; Adan Ayala(57) **CLAIM**

The ornamental design for a handheld cordless screwdriver, as shown and described.

DESCRIPTION

FIG. 1 is a left/front perspective view of a handheld cordless screwdriver showing my new design with the front portion in a first possible orientation relative to the rear portion.

FIG. 2 is a left side view thereof.

FIG. 3 is a right side view thereof.

FIG. 4 is a top plan view thereof.

FIG. 5 is a bottom plan view thereof.

FIG. 6 is a front view thereof.

FIG. 7 is a rear view thereof.

FIG. 8 is a left/front perspective view of a handheld cordless screwdriver showing my new design with the front portion in a second possible orientation relative to the rear portion.

FIG. 9 is a left side view thereof.

FIG. 10 is a right side view thereof.

FIG. 11 is a top plan view thereof.

FIG. 12 is a bottom plan view thereof.

FIG. 13 is a front view thereof; and,

FIG. 14 is a rear view thereof.
